UNITED STATES PATENT OFFICE.

OBERLIN SMITH, OF BRIDGETON, NEW JERSEY, AND MILES G. NIXON, OF CHICAGO,
ILLINOIS.

STRAP-LOCKING DEVICE.

1,207,233.

Specification of Letters Patent. Patented Dec. 5, 1916.

Application filed July 22, 1916. Serial No. 110,768.

To all whom it may concern:

Be it known that we, OBERLIN SMITH and MILES G. NIXON, citizens of the United States, said SMITH residing at Bridgeton, 5 in the county of Cumberland and State of New Jersey, and said NIXON residing at Chicago, county of Cook, State of Illinois, have invented certain new and useful Improvements in Strap-Locking Devices, of 10 which the following is a specification.

The object of our invention is to provide means by which a trunk-strap may be locked to a trunk by means of the trunk-lock and so prevent its being dropped off or stolen.

15 The following description and drawings make our invention clear.

In the various figures the same letter is used to designate the same part.

In Figures 1, 2 and 3, which are drawn 20 to a smaller scale than the other figures, are depicted the front elevation of that familiar type of trunk-lock in which the lock proper is contained in the upper part of a hinged hasp. Our device, however, when 25 designed especially for it, is entirely applicable to the older type of trunk-lock where the lock proper is attached to the trunk and its hasp attached to the lid or cover.

Fig. 1 is a side elevation of a trunk lock, 30 of well known construction, with which our invention is employed; Fig. 2 is a similar view thereof, but with the strap applied; Fig. 3 is a like view illustrating a different embodiment of our invention; Fig. 4 is a 35 front view of the device shown in Fig. 2, but without the lock or strap, and in an open position; Figs. 5 and 6 are bottom views thereof showing, respectively, the device before it is closed on the hasp and after it 40 has been closed thereon; Fig. 7 is a bottom view of another embodiment of our invention; Fig. 8 is a side view of the form shown in Figs. 5, 6 and 7; Figs. 9 to 12 are detail views of the device shown in Fig. 3; Fig. 9 45 being a front view thereof; Fig. 10 a view partially in horizontal section and partially in top plan; Fig. 11 a side view; Fig. 12 a view from the back but with the device arranged at an incline so that it appears in a 50 kind of perspective.

To illustrate our invention we show it applied to, or associated with the familiar type of trunk lock in which the lock proper is contained in the upper part of a hinged 55 hasp, but, of course, we do not limit our

selves to that particular type of trunk lock. Referring now to the drawings for a description somewhat in detail, the letter A designates the hasp of said type of trunk lock and B the socket casing thereof, these 60 parts being those, which, as is usual, are attached respectively to the body of the trunk and the lid of the trunk.

Referring particularly to the construction shown in Figs. 2, 4, 5 and 6, our device is 65 shown constructed of three parts, namely, the main member C, a flap E hinged thereto at one side and the pin F, which hinges the member C and the flap E, and in such construction the main member C and the flap 70 E are preferably stampings of sheet metal. The main member C comprises what in effect are three parallel bars, the middle one G of which is depressed, or offset, inward from the plane of the portions of the bars 75 above and below the same, and the strap D passes through the space lying between said two outer bars and said inner bar and in applying the device to the strap and hasp the portions of the main member C above and below the bar G are on the outer side of the strap and the hinge flap E lies between the inner side of the hasp A and the side of the trunk, and, hence, when the hasp is locked to the socket casing B, the flap E is inaccess- 80 85ible and can neither be gotten at nor moved to release the device from the strap; and as the main member C is provided, as clearly shown in Figs. 5 and 6, with an inturned end K that lies between the back of the hasp and the side of the trunk, it is impossible to swing the main member C upon the hinge 90 F and effect the release of the device from the hasp.

In Fig. 2 H is shown a stop riveted to 95 the strap. This member is sufficiently long to prevent its passing through the oblong area provided for the strap, and so prevents the removal thereof. A similar stop may be provided below the device at I but 100 may be dispensed with since the strap-buckle J will perform the function of the stop and prevent its withdrawal in this direction. With the strap in position as shown, to apply the device the hook-end K 105 is passed under one edge of the hasp A, the flap being open as in Fig. 5. After the device has been settled into the position shown in Figs. 5 and 6, the flap is closed in as in 110 Fig. 6. The hasp is pushed home and the

trunk is locked. Thus such locking incidentally locks in the device and the attached strap. After this the strap is buckled, the strap being free to slip and slide as demanded by the buckling, being, as clearly shown in Figs. 5 and 6, laced, or slid through the space provided in the main member C by offsetting the central portion G. In Fig. 7 a second flap L is substituted for the hook-end K, and performs the same function.

The alternate form front view, shown in Fig. 9, top view in Fig. 10, side view in Fig. 11 and a slightly inclined back view in Fig. 12, is a link of un-uniform section and consists of a single stamping or forging of metal. It is so shaped that the hasp A will fit into the lower part M of the device, holding it down when locked. Above the hasp A contained in the same oblong area is the strap D. The strap is rove through the device and the stop or stops riveted on. The device is then passed over the lock of the hasp as shown in Fig. 12, in which the strap is shown at D, the hasp at A, and the lock proper attached to the hasp, at N. The device is settled into position, the hasp is pushed home and locked which, as in the former case, prevents the removal of the strap; the latter is then buckled.

We claim:

1. The combination of a trunk lock having a hasp, a trunk strap, and a strap engaging element extending over the hasp and strap and having stops to limit sliding movement of the strap and prevent its separation from said element.

2. A device of the class described having

Copies of this patent may be obtained for five cents each, by addressing the "Commissioner of Patents, Washington, D. C."

means for attachment to the hasp of a lock, and a strap engaging element adapted to lie over the outer side of the hasp and serving to slidably confine a strap over the hasp.

3. A device of the class described comprising a member that extends on all four sides of the lock hasp, a portion on one side of the hasp being pivoted, and having a strap guide through which the strap has a limited sliding movement.

4. A device of the class described comprising a member that extends on all four sides of the lock hasp, a portion on one side of the hasp being pivoted and having a strap guide through which the strap has a limited sliding movement, said guide being formed by offsetting a portion of the member.

5. The combination with a lock having a hasp, a strap-securing device detachably connected with the hasp, and having on the outer side of the hasp an element that overlies the strap and allows sliding movement of the strap.

6. The combination with a lock having a hasp, a strap-attaching device comprising an element lying over the outer side of the hasp and confining the strap thereagainst, and a hinged flap lying at the back of the hasp.

In testimony whereof we affix our signatures in presence of two witnesses.

OBERLIN SMITH.
MILES G. NIXON.
